8 Claims. (Cl. 200—150)

1

This invention relates to electric circuit breakers in which the extinguishing of the arc is effected in an extinguishing chamber by one or more currents of quenching medium produced by the arc itself.

One object of the invention is to provide an improved circuit breaker.

A further object is to achieve efficient extinction of the arc by causing the quenching medium to flow through one or two hollow contacts.

A circuit breaker of the kind in which the arc is extinguished by one or more currents of quenching medium produced by the arc itself is provided according to the invention with an extinguishing chamber which comprises an arc chamber surrounded by a counter-pressure chamber, these latter two chambers coming into communication with each other by one or more apertures permitting an equalisation of the pressure in the arc chamber and the counter-pressure chamber by currents of quenching medium which pass through the arc, and the counter-pressure chamber enlarges when the pressure attains a pre-determined value.

Further objects and features of the invention appear from the following description read in conjunction with the accompanying drawing.

In the accompanying drawings three forms of circuit breaker according to the invention are illustrated by way of example,

Figure 1 being a sectional elevation of one circuit breaker,

Figure 2 a sectional elevation of a second circuit breaker,

Figure 3 a cross sectional view on the line AA 35 of Figure 2, and

Figure 4 a sectional elevation of a third circuit breaker.

Referring to Figure 1 of the said drawings, the circuit breaker comprises an arc chamber 1 surrounded by a counter-pressure chamber 2. A fixed contact 3 serves to make contact with the moving contact bar 4. This fixed contact 3 is pierced so that communication is established between the arc chamber 1 and the counter-pressure chamber 2, the latter being closed by a movable cover 5 which normally rests on a support ring 7. A spring 6, which is under constraint while at rest, is arranged above the movable cover 5 and does not permit the latter to move until the pressure in the counter-pressure chamber 2 attains a predetermined value. Apertures 8 formed in the cover 5 establish communications with the space 9 above the cover 5. The quenching medium may be a liquid (for example oil),

2

gaseous (for example an inert gas) or solid (inert powder). It fills the counter-pressure chamber 2 and part of the space 9.

The circuit breaker functions as follows. Assuming the quenching medium to be a liquid. Suppose that the movable contact bar 4 is connected to one pole of a source of current and that the fixed contact 3 is connected to the other pole so that the current flows through one contact to the other. When the contacts 3 and 4 are separated to break the current an arc is produced between them. The liquid in contact with the arc is vaporised and in consequence the arc is surrounded by a mass of gas at very high temperature which produces a sudden increase of pressure in the arc chamber 1. This increase in pressure is transmitted immediately to the counter-pressure chamber 2 by the aperture 3a in the pierced contact 3. When the arc is produced by the breaking of a small current the increase in pressure in the arc chamber 1 and in the counter-pressure chamber 2 is relatively small and is not capable of overcoming the pressure exerted by the spring 6 on the movable cover 5, so that the movable cover remains in the position shown in the drawing. A little fluid under pressure passes through the apertures 8 into the space 9. In consequence of this dispersal of part of the fluid contained in the counter-pressure chamber 2 the pressure in this chamber is reduced. The arc continuing to burn in the arc chamber 1 continues to vaporise the liquid so that the pressure in the arc chamber continues to increase. In consequence of the reduction of pressure in the counter-pressure chamber 2 there is established through the pierced contact 3 in which the base of the arc is burning a difference of pressure so that the quenching medium continues to leave the arc chamber 1 and enter the counter-pressure chamber 2. Under the action of the counter-pressure of the quenching medium contained in the counter-pressure chamber 2 the arc is comprised and this movement of the quenching medium has a particularly effective action in extinguishing the arc.

When the arc is extinguished the increase in pressure immediately ceases. The remainder of the gases producing the pressure leaves the arc chamber 1 and enters the counter-pressure chamber 2. It is only when the gases have entered the space 9 by passing through the apertures 8 that the quenching medium contained in the chambers 1 and 2 is no longer under pressure, which results in a favourable extinguishing action.

When a large current is broken the increase in pressure is transmitted in a similar way from the arc chamber 1 to the counter-pressure chamber 2. In consequence of the great increase in pressure the force exerted on the movable cover 5 is sufficient to overcome the force of the spring 6 in spite of the apertures 8. The movable cover 5 is therefore forced upwards. In consequence of this movement the volume of the counter-pressure chamber 2 is increased and the danger of an excessive pressure rise is obviated. The arc burning in the pierced contact 3 is blown out in an efficient manner and is quenched by the current of quenching medium and compressed by the counter-pressure of the quenching medium contained in the chamber 2. Because of the pressure exerted by the spring 6 on the movable cover 5 the counter-pressure adjusts itself according to the movement of quenching medium produced by the arc depending upon the strength of the broken current so that there is always produced a current of quenching medium favourable for extinguishing the arc.

The blowing out of the arc in the pierced contact 3 under the action of the counter-pressure 25 of the quenching medium in the chamber 2 is of great importance in extinguishing the arc. This counter-pressure produces an accumulation of pressure in the quenching medium in the arc chamber 1 as well as in the counter-pressure chamber 2. Equilisation of the pressure between the arc chamber and the counter-pressure chamber does not take place suddenly by a rapid change from maximum to minimum pressure, but there is maintained a current of some duration 30 between the limits of a predetermined range of pressure. An increase of pressure takes place while the arc continues to burn in spite of the expulsion of quenching medium.

Referring to Figure 2 of the drawings, the extinguishing chamber comprises an arc chamber 16 surrounded by a counter-pressure chamber 17. A fixed contact 15 provided with an aperture 15a is arranged in the chamber 16 and its complementary contact is a movable contact bar 18. This bar 18 is bored for part of its length and is provided with slits 19 which establish communication between the arc chamber 16 and the counter-pressure chamber 17 when the contact bar 18 is separated from the fixed contact 15. The length of the tubular part 29 at the end of the bar 18 is such relatively to the point where the slits 19 commence that the various pressure compartments 21 are closed, in spite of the slits 19, by the extremity of the bar 18 in such a way that the quenching medium is constrained to pass out through the extremity of the bar 18.

The arc chamber 16 is closed at its upper end by a tube 22 in which are formed apertures 23. The counter-pressure chamber 17 is closed by a movable lid 24 in which are formed apertures 27 and which, in the position shown, is urged against a ring 26 by a compression spring 25. Additional quenching medium is accommodated in the space 28 above the movable lid 24.

The circuit breaker functions as follows when filled with a liquid quenching medium. When the contacts 15 and 18 are separated there is produced in the arc chamber 16 an arc which 70 lengthens and causes an increase of pressure. The arc chamber 16 and the counter-pressure chamber 17 are now in communication through the pierced contact 15 and by the hollow part of the contact bar 18 through the slits 19 and 75

the apertures 23 so that the increase of pressure is partially transmitted to the counter-pressure chamber. In the case of an arc produced by the breaking of a small current the increase in pressure is relatively small. This increase in pressure is not capable of overcoming the force exerted by the spring 25 on the movable lid 24. Part of the quenching medium contained in the counter-pressure chamber is expelled through the apertures 27 under the action of the small increase in pressure. These apertures are so dimensioned that an increase in pressure is maintained in the counter-pressure chamber 17 in spite of the expulsion of part of the quenching medium. The contact bar 18 continuing to rise, the arc continues to lengthen and produce further increases in pressure in the arc chamber 16. The slits 19 pass before the apertures 23, maintaining communication with the counter-pressure chamber 17, while the pierced contact 15 maintains communication at the other end. The arc burns with one of its striking points in the pierced contact 15 and the other striking point in the hollow bar 18. In consequence of the fall in pressure in the counter-pressure chamber 17 there is established through the pierced contacts 15 and 18 a pressure which gives rise to a double current of quenching medium directed towards the two striking points of the arc. Each of these striking points is thus subjected to the action of a current of quenching medium such that the arc is readily extinguished. The extremity 29 of the contact bar 18 has a length such that it always closes those chambers 21 which it traverses so that the current of quenching medium is constrained to pass through the extremity of the contact bar and blow out the arc which burns at that point.

When a large current is broken the force of the spring 25 acting on the movable lid 24 is overcome and the volume of the counter-pressure chamber 17 is increased, preventing excess pressure in that chamber. The counter-pressure of the quenching medium contained in the counter-pressure chamber exercises a similar action to that which has been described above. The two currents of quenching medium ensure an efficient extinction of the arc.

Referring to Figure 4 of the accompanying drawings, the circuit breaker comprises an arc chamber 48 surrounded by a counter-pressure chamber 49, a fixed contact 50, a contact bar 51, a movable cover 33, a spring 52, apertures 53 in the movable cover and a space 54 above the movable cover. The arc chamber 48 is secured by means of a supporting ring 30 on the base 31 of the apparatus. It is extended upwardly into a tubular part 32 in which may move the contact bar 51. On the extension of the said chamber is a shoulder which serves to locate the cover 33. On the upper part is secured a ring 34 against which the spring 52 abuts. The external wall 55 of the counter-pressure chamber is sealed by means of a sealing-joint 36 in a flange 35 secured by the supporting ring 30. At the top of the space 54 is arranged a cover 37 with a sealing-joint 38. The interior of the arc chamber 48 communicates at its lower end through apertures 39 and at its upper end through apertures 56 with the counter-pressure chamber 49. A fixture 40 is arranged inside the arc chamber 48, and is divided throughout its height by partitions 41 into a series of compartments 42 each partition having an aperture through which passes the contact bar 51. This contact

bar 51, the lower part of which is hollow, is provided with longitudinal slits 45 similar to the slits 19 in Figure 2. The upper surfaces 46 and 47 of the apertures 39 and 56 and also the lower faces of the partitions 41 and the lower parts of the apertures 53 are inclined so as to prevent the formation of stationary bubbles and pockets of gas. The arc chamber 48 serves not only as an arc chamber but also to support the moving parts of the circuit breaker and so distributes to the different parts the mechanical forces which arise during the functioning of the apparatus.

The apparatus functions as follows. Suppose that the contact bar 51 is in the position 51a in which it is in contact with the annular contact 50 so that the current passes from the base-plate 31 to the contact bar 51. If the latter is displaced upwardly an arc is produced between the contact bar 51 and the annular contact 50. This arc gives rise to a sudden increase in pressure in the quenching medium, for example an extinguishing liquid, which fills the apparatus as far as the surface 46. This increase in pressure is transmitted through the apertures 39 and 56 and the slits 45 in the bar 51 to the counter-pressure chamber 49. Under the action of this sudden increase in pressure the cover 33 is raised against the action of the spring 52. Owing to the arrangement of the apertures 39 and 56 and of the compartments 42 and the apertures 53 any gas which may be generated cannot form into stationary pockets. The pressure which is established almost immediately results in a very rapid flowing of quenching medium on to the arc which as a result is extinguished immediately. The mechanical forces which arise during the quenching of the arc, the effect of the rapid rise in pressure, are transmitted by means of the movable cover 33 and the spring 52 to the arc chamber itself which absorbs these forces. The movable cover 33 assists in dissipating the momentary forces.

The construction of the arc chamber in accordance with the invention ensures a great solidity and certainty in action so as to influence favourably a quenching of the arc.

In all the described circuit-breakers, the counter-pressure produces an accumulation of pressure in the quenching medium in the arc chamber so that the arc is compressed, whereas the difference between the pressures in the arc chamber and the counter-pressure chamber and the rate of flow between these chambers is as great as if no counter-pressure were exerted. The arc, being compressed, is more rapidly extinguished.

What I claim and desire to secure by Letters Patent is:

1. An electric circuit breaker of the kind in which the arc is extinguished by at least one current of quenching medium produced by the arc itself, comprising an arc chamber, a fixed perforated electric contact in a wall of said arc chamber, a movable electric contact having one end capable of moving within said arc chamber into and out of contact with said fixed contact, a counter-pressure chamber surrounding said arc chamber, a quenching medium at least partially filling said arc chamber and said counter-pressure chamber, and at least one of the members which form said counter-pressure chamber being displaceable by excess pressure in said quenching medium in said arc chamber and said counter-pressure chamber whereby under excess

pressure the internal volume of said counter-pressure chamber is increased, the arrangement being such that the counter-pressure of the quenching medium in the counter-pressure chamber produces a corresponding accumulation of pressure in the quenching medium in the arc chamber and the arc is compressed.

2. An electric circuit breaker of the kind in which the arc is extinguished by at least one current of quenching medium produced by the arc itself, comprising an arc chamber, a fixed perforated electric contact in a wall of said arc chamber, a movable electric contact having one end capable of moving within said arc chamber into and out of contact with said fixed contact, a counter-pressure chamber surrounding said arc chamber, a quenching medium at least partially filling said arc chamber and said counter-pressure chamber, and at least one of the members which form said counter-pressure chamber being spring-loaded and slidably displaceable by excess pressure in said quenching medium in said arc chamber and said counter-pressure chamber whereby under excess pressure the internal volume of said counter-pressure chamber is increased, the arrangement being such that the counter-pressure of the quenching medium in the counter-pressure chamber produces a corresponding accumulation of pressure in the quenching medium in the arc chamber and the arc is compressed.

3. An electric circuit breaker of the kind in which the arc is extinguished by at least one current of quenching medium produced by the arc itself, comprising an arc chamber, a fixed perforated electric contact in a wall of said arc chamber, a movable electric contact having one end capable of moving within said arc chamber into and out of contact with said fixed contact, a counter-pressure chamber surrounding said arc chamber, a quenching medium at least partially filling said arc chamber and said counter-pressure chamber, and at least one of the members which form said counter-pressure chamber being apertured and spring-loaded and slidably displaceable by excess pressure in said quenching medium in said arc chamber and said counter-pressure chamber whereby under excess pressure the internal volume of said counter-pressure chamber is increased, the arrangement being such that the counter-pressure of the quenching medium in the counter-pressure chamber produces a corresponding accumulation of pressure in the quenching medium in the arc chamber and the arc is compressed.

4. An electric circuit breaker of the kind in which the arc is extinguished by at least one current of quenching medium produced by the arc itself, comprising an arc chamber, a fixed perforated electric contact in a wall of said arc chamber, a movable electric contact having one end capable of moving within said arc chamber into and out of contact with said fixed contact, a counter-pressure chamber surrounding said arc chamber, a quenching medium at least partially filling said arc chamber and said counter-pressure chamber, one of the members forming said counter-pressure chamber being apertured and spring-loaded and slidably displaceable by excess pressure in said quenching medium in said arc chamber and said counter-pressure chamber whereby under excess pressure the internal volume of said counter-pressure chamber is increased, and said movable contact being at its contact end tubular and apertured and thereby

affording passage for said quenching medium from said arc chamber to said counter-pressure chamber, the arrangement being such that the counter-pressure of the quenching medium in the counter-pressure chamber produces a corresponding accumulation of pressure in the quenching medium in the arc chamber and the arc is compressed.

5. A circuit breaker as claimed in claim 4, wherein said counter-pressure chamber and said spring-loaded slidably displaceable member are mounted on said arc chamber and said arc chamber absorbs the mechanical forces acting within the device during functioning.

6. An electric circuit breaker of the kind in which the arc is extinguished by at least one current of quenching medium produced by the arc itself, comprising an arc chamber, a fixed perforated electric contact in a wall of said arc chamber, a movable electric contact having one end capable of moving within said arc chamber into and out of contact with said fixed contact, a counter-pressure chamber surrounding said arc chamber, a quenching medium at least partially filling said arc chamber and said counter-pressure chamber, one of the members forming said counter-pressure chamber being apertured and spring-loaded and slidably displaceable by excess pressure in said quenching medium in said arc chamber and said counter-pressure chamber whereby under excess pressure the internal volume of said counter-pressure chamber is increased, and said movable contact being at its contact end tubular and apertured and thereby affording passage for said quenching medium from said arc chamber to said counter-pressure chamber, and the upper part of said arc chamber being tubular, and a compression spring externally mounted on said tubular upper part of said arc chamber and engaging said slidably displaceable member, said slidably displaceable member being slidable on said tubular upper part of said arc chamber, the arrangement being such that the counter-pressure of the quenching medium in the counter-pressure chamber produces a corresponding accumulation of pressure in the quenching medium in the arc chamber and the arc is compressed.

7. An electric circuit breaker of the kind in which the arc is extinguished by at least one current of quenching medium produced by the arc itself, comprising an arc chamber, a fixed perforated electric contact in a wall of said arc chamber, a movable electric contact having one end capable of moving within said arc chamber

into and out of contact with said fixed contact a counter-pressure chamber surrounding said arc chamber, a quenching medium at least partially filling said arc chamber and said counter-pressure chamber, one of the members forming said counter-pressure chamber being apertured and spring-loaded and slidably displaceable by excess pressure in said quenching medium in said arc chamber and said counter-pressure chamber whereby under excess pressure the internal volume of said counter-pressure chamber is increased and said movable contact being at its contact end tubular and apertured and thereby affording passage for said quenching medium from said arc chamber to said counter-pressure chamber and the upper part of said arc chamber being tubular, and a compression spring externally mounted on said tubular upper part of said arc chamber and engaging said slidably displaceable member, said slidably displaceable member being slidable on said tubular upper part of said arc chamber, and said arc chamber being internally compartmented and the compartments being successively closed during circuit-breaking by said tubular end of said movable contact whereby quenching medium is caused to pass through the arc in escaping through said tubular end, the arrangement being such that the counter-pressure of the quenching medium in the counter-pressure chamber produces a corresponding accumulation of pressure in the quenching medium in the arc chamber and the arc is compressed.

8. A circuit breaker as claimed in claim 7, having all downwardly facing surfaces in said arc chamber and said spring-loaded member inclined to the horizontal and thus leading away any gas bubbles produced during functioning.
